(57) **CLAIM**

The ornamental design for a decking, as shown and described.

DESCRIPTION

FIG. 1 is a top perspective view of the decking showing the new design;

FIG. 2 is a front elevational view of the decking showing the new design;

FIG. 3 is a rear elevational view of the decking showing the new design;

FIG. 4 is a top plan view of the decking showing the new design;

FIG. 5 is a right-side elevational view of the decking showing the new design;

FIG. 6 is a left-side elevational view of the decking showing the new design;

FIG. 7 is a bottom plan view of the decking showing the new design;

FIG. 8 is a front elevational view of a second embodiment of the decking showing the new design having a height different than that of the decking shown in FIGS. 1-7, all other features are the same; and,

FIG. 9 is a front elevational view of a third embodiment of the decking showing the new design having a height different than that shown in FIGS. 1-8, all other features are the same.

The decking has been broken in the center to show indefinite length.

1 Claim, 3 Drawing Sheets
